UNITED STATES PATENT OFFICE

2,148,384

TRANSMISSION SYSTEM

Hansheinrich Verse, Braunschweig, Germany, assignor to General Electric Company, a corporation of New York

Application August 1, 1938, Serial No. 222,480
In Germany February 22, 1937

5 Claims. (Cl. 171—97)

My invention relates to direct current power transmission systems and more particularly to such systems utilizing electric valve translating apparatus at the transmitting and receiving ends.

In direct current power transmission systems utilizing electric valve translating apparatus at the transmitting and receiving ends it has been found difficult to place the transmission system into operation in such systems where no neutral wire has been provided and more particularly in such systems where the electric valve translating apparatus utilizes electric arc discharge valves of the type described in a book by Erwin Marx entitled "Lichtbogenstromrichter" published in Berlin in 1932, and in United States Letters Patent No. 2,074,930 granted March 23, 1937, upon the application of Erwin Marx. In such systems it has been customary to provide a continuous flow of gas, such as air, between the electrodes of the valves. In some of the arrangements the principal pair of electrodes has been provided with an auxiliary electrode which serves as a starting or ignition electrode. It has been customary in such arrangements to operate the valves with an ignition moment displaced by

$$\frac{360^\circ}{2m}$$

where m equals the number of phases in each translating apparatus, in order to obtain the advantages of a $2m$ phase direct current voltage ripple. If the time during which the auxiliary arc operates and the type of rectifier is very short or if in the instance of the usual gaseous type electric valve the ignition impulse is very short, then such transmission system cannot start up in the absence of sufficient valve capacity or leakage paths. After two of the valves in each of the translating apparatus have become conductive the translating apparatus and transmission system will continue to function in its normal manner.

It has been suggested that a direct current neutral wire be utilized to interconnect the neutral points of the networks of each of the translating systems in order to obviate the difficulties of starting the transmission system, but when this wire is added it has the disadvantage that the direct current ripple is only m -phase or of the fundamental frequency. In accordance with my invention a starting impedance or resistance is connected between the neutral points of the inductive network and the ground in each electric valve translating system so that this impedance cooperates with the line-to-ground capacitance

of the transmission line to permit the necessary number of valves in each translating system to become conductive. As the same time the advantage of obtaining a $2m$ phase direct current voltage ripple is maintained.

It is therefore an object of my invention to provide a transmission system utilizing electric valve translating or converting apparatus which will overcome certain limitations of the arrangements of the prior art, and which will be simple and reliable in operation.

It is another object of my invention to provide an arrangement for facilitating the starting of the electric valve translating apparatus in a direct current transmission system.

The novel features which are believed to be characteristic of my invention are set forth with particularity in the appended claims. My invention itself, however, both as to its organization and method of operation together with further objects and advantages thereof, will be better understood by reference to the following description taken in connection with the accompanying drawing in which Fig. 1 shows a direct current transmission system utilizing a plurality of electric valve translating apparatus employing the valves of the type described by Erwin Marx in the reference referred to above; and Fig. 2 discloses the application of my invention to a direct current transmission system utilizing a different arrangement of electric valve translating system in which there are employed valves of the type in more common use in the art at the present time.

Referring now more particularly to Fig. 1 of the drawing, there is disclosed an arrangement embodying my invention for transmitting energy from the alternating current supply circuit 10 to the alternating current load circuit 11 by means of an electric valve translating apparatus 12, a direct current transmission line 13 and an electric valve translating apparatus 14. The electric valve translating apparatus 12 includes a transformer having a primary winding 15 connected to the alternating current supply circuit 10, and a secondary winding 16 arranged in star relation so as to provide a neutral point. The outer extremities of the secondary winding 16 are each connected to both sides of the direct current transmission line 13 by means of a plurality of pairs of valves 17, 18; 19, 20; 21, 22. Thus the valves 17, 19 and 21 are connected to one side of the direct current transmission line 13 through a suitable smoothing reactor 23 and the remaining valves 18, 20 and 22 are connected through a suit-

able smoothing reactor 24 to the other side of the direct current transmission line 13. The electric valve translating apparatus 14 receives energy from the direct current transmission line 13 through suitable smoothing reactors 25 and 26, and a plurality of pairs of valves 27, 28; 29, 30; 31, 32, interconnect the outer extremities of a transformer having a primary winding 33 with the direct current circuit. This transformer is provided with a secondary winding 34 which is connected to the alternating current load circuit 11. While for the purposes of illustration I have shown the electric valves 17 to 22 and 27 to 32 as being of the type described by Erwin Marx since such systems utilizing valves of this type appear to be more difficult to start than those using other types of valves, it of course will be understood that the invention is equally applicable to systems using any of the valves commonly utilized in the art. The valves shown in Fig. 1 comprise two principal electrodes and an auxiliary or starting electrode and a gaseous fluid medium is circulated between the principal electrodes. In accordance with my invention the neutral point of the transformer winding 16 of the electric translating apparatus 12 is connected to the ground through a resistor or impedance 35, and similarly the neutral point of the transformer winding 33 of the electric valve translating apparatus 14 is connected through a suitable resistor or impedance 36 to the ground. The capacitance-to-ground of each of the conductors of the transmission line 13 is represented by capacitors 37 and 38 shown in dotted lines. The impedances 35 and 36 cooperate with capacitances 37 and 38 to provide during the starting operation of the transmission system a leakage path sufficient to facilitate the starting of the transmission system. It will be apparent to those skilled in the art that the difficulty of obtaining absolute synchronism in the moment of ignition of two of the valves of the translating apparatus 12 for example, is the cause of some of the difficulty encountered in placing the transmission system into operation. In addition to this difficulty it is also apparent that the moment of ignition of any pair of valves of the translating apparatus 14 is generally phase displaced with respect to the moment of ignition of a similar pair of valves in the translating apparatus 12. The leakage path provided by the impedances 35 and 36 thus permits in the arrangement shown two valves in each of the translating apparatus to become fully conductive so that normal operation of the transmission system will continue.

In Fig. 2 I have shown the application of my invention to a direct current transmission system operating between the alternating current supply circuit 40 and the alternating current load circuit 41. This system includes an electric valve translating or rectifying apparatus 42, a direct current transmission line 43 and an electric valve translating or inverting apparatus 44. The electric valve translating apparatus 42 includes a transformer having a primary winding 45 connected to the alternating current source 40 and a pair of secondary windings 46 and 47. The neutral point of the secondary transformer winding 46 is connected to one side of the direct current transmission line 43 through a suitable smoothing reactor 48, and the outer extremities of this transformer winding are connected through a plurality of valves 49, 50 and 51 to the neutral point of the transformer secondary winding 47. The outer extremities of this

latter transformer winding 47 are each connected by one of a plurality of valves 52 to 54 through a suitable smoothing reactor 55 to the other side of the direct current transmission line 43. One side of the direct current transmission line 43 is connected through a suitable smoothing reactor 56 to the neutral point of one of the primary windings 57 of a transformer having a second primary winding 58 and a secondary winding 59 which is connected to the alternating current load circuit 41. The outer extremities of this primary winding 57 are each connected through one of a plurality of valves 60 to 62 to the neutral point of the other primary winding 58 of this same transformer. The outer extremities of this latter winding 58 are each connected to one of a plurality of valves 63 to 65 through a suitable smoothing reactor 66 to the other side of the direct current transmission line 43. In accordance with my invention I connect an electric translating apparatus 42 and impedance 67 between the neutral points of the transformer winding 47 and the ground. This point of connection, as will be apparent from an inspection of the circuit arrangement, is a connection between the midpoint of the electric valve translating apparatus and the ground. This impedance 67 cooperates with the capacitance-to-ground of the transmission line 43 indicated by the capacitors 68 and 69 to provide a leakage path across each of the valves and their associated inductive networks. Similarly, an impedance or resistance 70 is connected between the neutral points of the transformer winding 58 and the electric valve translating apparatus 44 and the ground to provide the necessary leakage paths which include the capacitances 68 and 69 of the direct current transmission line 43. It is preferable in either of the circuit arrangements disclosed in the drawing to select impedance devices having a relatively high resistance value since it is only necessary to pass a minimum current sufficient to permit the valves to start.

While my invention has been described as applied to a transmission system, it will be apparent to those skilled in the art that it is equally applicable to a full wave rectifier and in this instance a resistor or impedance is connected between the neutral point of the electric valve converting apparatus and the neutral point on the load circuit. It will furthermore be apparent that if the capacitance of the transmission line to ground is insufficient additional capacitors may be utilized or a high impedance may be connected across the transmission line, the neutral point of which is grounded.

While I have shown particular applications of my invention to electric transmission systems, it is to be understood that this is merely illustrative as to but a few of the electric valve transmitting apparatus and transmission systems to which my invention may be applied. It will, of course, be understood that I do not wish to be limited thereto, since it is apparent that the principles herein disclosed are susceptible of numerous other applications, and modifications may be made in the circuit arrangements to which my invention may be applied without departing from the spirit and scope of my invention as set forth in the appended claims.

What I claim as new and desire to obtain by Letters Patent of the United States is:

1. The combination comprising a supply circuit, a load circuit, a plurality of electric valve translating apparatus and a transmission line in-

terconnecting said circuits, each of said translating apparatus comprising an inductive network provided with a neutral point and a plurality of pairs of series-connected electric arc discharge valves connected across said transmission line and an impedance means for each network connected between the neutral points thereof and the ground, said impedances cooperating with the capacitance-to-ground of said transmission line to facilitate the starting of said translating apparatus.

2. The combination comprising an alternating current circuit, a direct current circuit, one of said circuits having an appreciable capacitance-to-ground, an electric translating apparatus interconnecting said circuits and comprising an inductive network provided with a neutral point, and a plurality of pairs of electric arc discharge valves connected in series across said direct current circuit, and impedance means for said network connected between the neutral point thereof and the ground, said impedance cooperating with the capacitance-to-ground of one of said circuits to facilitate the starting of said translating apparatus.

3. The combination comprising a supply circuit, a load circuit, a plurality of electric valve translating apparatus and a transmission line interconnecting said circuits, each of said translating apparatus comprising an inductive network provided with a neutral point and a pair of electric arc discharge valves interconnecting each terminal of said network with both sides of said transmission line, and means for facilitating the

starting of the valves of said apparatus comprising a plurality of impedances each connected between the ground and the neutral point of each inductive network.

4. The combination comprising a supply circuit, 5 a load circuit, a plurality of electric valve translating apparatus and a transmission line interconnecting said circuits, each of said translating apparatus comprising an inductive network provided with a neutral point and a pair of electric 10 arc discharge valves interconnecting each terminal of said network with both sides of said transmission line, and an impedance means for each network connected between the neutral point thereof and the ground, said impedances cooperating with the capacitance-to-ground of said transmission line to facilitate the starting of said translating apparatus. 15

5. The combination comprising alternating current supply and load circuits, a plurality of 20 electric valve translating apparatus and a direct current transmission line interconnecting said circuits, each of said translating apparatus comprising an inductive network provided with a neutral point and a pair of electric arc discharge 25 valves interconnecting each terminal of said network with both sides of said direct current transmission line, and an impedance means for each network connected between the neutral point thereof and the ground, said impedances cooperating with the capacitance-to-ground of said transmission line to facilitate the starting of the 30 valves of said translating apparatus.
